Term of patent 14 years

(Cl. D34—5)

FIG. 1.

FIG. 2.

FIG. 1 is a top perspective view of one form of an educational game board according to our new design, wherein the pattern is applied to a rectangular-shaped board and is provided with home pathways extending inwardly from the two long sides of the board;

FIG. 2 is a top plan view of a slightly modified form of educational game board according to our new design, wherein the generic pattern common to both forms is applied to a square-shaped board and is provided with home pathways extending inwardly from each of the sides.

The dominant features of our design reside in the portions shown in full lines.

We claim:

The ornamental design for an educational game board or similar article, substantially as herein shown and described.
